UNITED STATES PATENT OFFICE.

ABRAHAM FRANK, OF NEW YORK, N. Y.

DESIGN FOR A PLASTRON OR WAIST.

SPECIFICATION forming part of Design No. 22,040, dated December 6, 1892.

Application filed November 3, 1892. Serial No. 450,910. Term of patent 7 years.

To all whom it may concern:

Be it known that I, ABRAHAM FRANK, a citizen of the United States, residing at New York, in the county and State of New York, have invented and produced a new and original Design for a Plastron or Waist, of which the following is a specification.

This design has for its object to provide a novel and ornamental plastron or waist; and it consists in a plastron or waist having a series of stripes of contrasting shades and a belt provided with a series of ornaments in the form of conventional representations of stars.

The design is illustrated by the accompanying drawing, in which the figure shows the plastron or waist in elevation.

In the drawing the letter A indicates the plastron or waist, having stripes B C of contrasting shades. The belt D is provided with

a series of ornaments E in the form of conventional representations of stars. The collar F is also shown striped.

The design provides a novel and ornamental plastron or waist, which presents a distinguishing and characteristic appearance to the eye.

What I claim as new, and desire to secure by Letters Patent, is—

The design for a plastron or waist, substantially as shown and described.

In testimony whereof I have hereunto set my hand in the presence of two subscribing witnesses.

ABRAHAM FRANK.
